UNITED STATES PATENT OFFICE.

HORACE C. KNERR, OF PRIMOS, PENNSYLVANIA.

CONTROL SYSTEM.

1,228,030.

Specification of Letters Patent. Patented May 29, 1917.

Application filed December 1, 1914. Serial No. 874,956.

To all whom it may concern:

Be it known that I, HORACE C. KNERR, a citizen of the United States, residing at Primos, county of Delaware, and State of Pennsylvania, have invented a new and useful Control-System, of which the following is a specification.

My invention relates to a system of control wherein a translating device is caused to consecutively respond to or is caused to be consecutively actuated or energized by closely succeeding, simultaneous or overlapping electrical control currents or impulses of current.

10 More particularly my invention resides in a system for consecutively controlling, actuating or energizing a signal setting or signal clearing mechanism or apparatus in response to closely successive or substantially simultaneous or overlapping signal control impulses; and my invention resides also in such a system in which the signaling apparatus comprises a step-by-step mechanism or car counting mechanism.

15 While the foregoing is one of the applications of my invention, it will be understood that my invention is not limited as to the nature of the translating device controlled by the system, and is not limited to 20 the signaling art, except where so expressly stated in the claims.

For an illustration of several of the forms my invention may take, reference is to be had to the accompanying drawings, 25 in which:

Figure 1 is a diagrammatic view of an application of my invention to a railway signaling system, involving step-by-step or car counting mechanism.

30 Fig. 1^a is a detail of a contact for cooperation with another contact for effecting circuit control only upon relative movement of said contacts in a predetermined direction with respect to each other.

35 Fig. 2 is a diagrammatic view illustrating a modified arrangement of my invention of Fig. 1 and a time element device associated therewith.

Fig. 3 is a diagrammatic view of a further modification of my invention.

40 Fig. 4 is a diagrammatic view of another modification of my invention.

Fig. 5 is a diagrammatic view, partly in perspective, illustrating a further modification of my invention.

Fig. 6 is a fragmentary elevational view of part of the mechanism of Fig. 5.

Referring to Fig. 1, 1 represents a contact conductor, such as a trolley wire, third rail, or the like, of an electric railway system, 60 on an independent signal conductor, whose return conductor will be assumed to be the earth or running rails, though any other return conductor may be employed.

At various points along the railway are 65 disposed the vehicle controlled contacts c_1 , c_2 , c_3 , c_4 , and c_5 which are adapted to be brought into electrical communication with the conductor 1 in the manner well understood in the signaling art, for effecting certain signal controls. All of these vehicle controlled contacts may be required to control one and the same signaling apparatus. And inasmuch as it may often happen that more than one of these vehicle controlled 70 contacts is brought into communication with the conductor 1 at the same or substantially the same time, or at relatively short intervals of time from each other, the signaling apparatus would not properly respond to 75 the control that should be effected by each of such vehicle controlled contacts unless recourse were had to a system of the character herein described. Here, by way of example, a signal setting electro-magnet S is required 80 to be controlled by each of the vehicle controlled contacts without confusion or failure due to the bringing of two or more of the vehicle controlled contacts into communication with the conductor 1 simultaneously or 85 substantially simultaneously, or at two short intervals of time after each other. If the energization of the electro-magnet were to follow exactly the connection of each of the vehicle controlled contacts to the conductor 1, it will readily be seen that the energizations of the magnet S would not 90 always be separate and distinct, but that there would be a confusion or running together of the controls, with resultant imperfect operation of the signaling system.

Here the electro-magnet S is shown as having the movable armature or core 2 which, upon being attracted upon energization of the electro-magnet S compresses the 105 spring 3 and moves the member 4 toward the right, and in so doing causes the pawl 5 to engage the notched wheel 6 to move the same around in counter-clockwise direction one step. The wheel 6 is secured upon a 110

shaft 7 which drives a switch disk 8 upon which continuously bears the brush 9 connected by conductor 10 to the conductor 1. In normal position the brush 11 bears upon the lug 12 of the disk 8, thereby allowing current to flow from conductor 1 through conductor 10, brush 9, disk 8, lug 12 and brush 11, through conductor 13 through the winding of the thus normally energized electro-magnet H whose other terminal is connected to earth or return conductor E. Electro-magnet H, therefore, holds its armature 14 in attracted position illustrated, thereby holding the rod 15, passing through guide 16, against the tail or counterweight 17 of the arm 18, pivoted at 19, and carrying the semaphore or signal disk 20. Electro-magnet H so holds the disk 20 in the position shown against the effect of gravity which biases it toward the indicating or display position indicated by the dotted circle at 20^a.

The brush 9 connects by conductor 21 with one terminal of the electric signal lamp 22 whose other terminal is connected to the contact 23 adapted to be engaged by the armature 14, which is connected to the earth or return conductor E.

It will accordingly be understood that upon first energization of the electro-magnet S, the wheel 6 is stepped around one notch, thus breaking the circuit between the lug 12 and the brush 11, thereby deenergizing the electro-magnet H, whereupon the rod 15 drops with armature 14, and gravity moves the disk 20 to the display position 20^a. And when the armature 14 drops it engages contact 23, whereupon the signal lamp 22 glows and gives a further signal indication.

And, as well understood in the signaling art, each successive energization of electro-magnet S, as by operation of one or more of the switches c₁, c₂, etc., which may be vehicle controlled, will step the wheel 6 around another step, without, however, affecting the display of signals 20 and 22, since element 12 remains out of contact with element 11, this action usually resulting upon the entry of a plurality of trains or cars into a section or block. And it is well understood in the art of signaling that upon the departure of each of such trains or cars from the block the wheel 6 may be stepped around in clockwise direction one notch or step for each car or train leaving a block by an electro-magnet which may be similar to the electro-magnet S and similarly controlled. And it will therefore be understood that another electro-magnet, a signal clearing magnet, may be associated with the wheel 6 to step it in opposite direction, which clearing magnet may be controlled by a system of the character controlling the magnet S about to be described, other vehicle controlled contacts and

associated magnets serving for this purpose. When all of the cars have left the block the switch disk 8 will have been stepped back to its original position, thus again causing the engagement of contacts 11 and 12. As an illustration of such a two-way step-by-step device, see the patent to Nachod No. 1,108,127, September 1, 1914.

The vehicle controlled contacts c₁ to c₅ control the electro-magnets M₁ to M₅, respectively, one terminal of each of these magnets being connected to the earth or return conductor E while their remaining terminals connect respectively with these vehicle controlled contacts.

Each of these electro-magnets, except M₁, is provided with an additional coil, termed a holding coil, these holding coils being indicated at C₂, C₃, C₄ and C₅. These coils are shown connected in series with each other between the contact m' and the earth or return conductor E. Thus, one terminal of the holding coil C₂ is connected to the contact m₁ and its other terminal to the contact m₂ and one terminal of the coil C₃ whose other terminal is connected to the contact m₃ and to one terminal of the coil C₄ whose other terminal is connected to the contact m₄ and to one terminal of the coil C₅ whose other terminal connects to the earth or return conductor E.

The magnets M₁ to M₅ are provided, respectively, with the armatures a₁ to a₅, the armatures a₁ to a₄ adapted to engage, respectively, the contacts m₁ to m₄ when the magnets M₁ to M₄ are energized, and the armature a₁ is connected to conductor 24, which connects through conductor 10 with the conductor 1. The armatures a₂, a₃ and a₄ are connected through the resistances r₂, r₃ and r₄, respectively, with the conductor 24.

Actuated by and movable with the armatures a₁ to a₅, respectively, are the movable switch levers or elements b₁ to b₅, all electrically connected to the conductor 24 and adapted to engage, respectively, the stationary contacts d₁ to d₅, all of which are connected to the conductor 25 connecting to one terminal of the electro-magnet S whose other terminal connects to the return conductor or ground E.

The arrangement of the movable switch elements b₁ to b₅ and their stationary coöperating contacts d₁ to d₅ is such that on the upward stroke of the members b₁ to b₅ they do not contact with their coöperating stationary contacts, but do engage and contact with them on their return or down stroke. This may be accomplished by the arrangement such as illustrated in Fig. 1^a, where it will be seen that each of the contacts, as d₁, has substantial vertical extent and has on its back a mass of insulating material 26, the upper end of the composite member d₁, 26

being bent, curved or deflected toward the right, while the lower end is deflected or curved toward the left. The member b_1 in making a complete passage upwardly and downwardly passes entirely around the member d_1 , 26; in the upstroke passing along the insulating material 26 and then finally being deflected thereby slightly to the right, and when it clears the upper end springs 10 slightly toward the left, by its own resiliency, and in returning downwardly wipes against the contact d_1 and at the lower end of its travel is deflected toward the left, and when passing beyond the same in reaching 15 its lowermost position springs to the right and is then ready for the next upward movement in engagement with the insulation 26.

It will be understood that the contacts m_1 to m_4 are engaged by their respective armatures a_1 to a_4 immediately they begin to move in their upward travel, and continue so in contact until they have again fallen to nearly the lower limits of their travel.

It will be understood that each of the magnets M_1 to M_5 has such power that when energized it can attract its armature upwardly and carry with it the associated switching element; and it will be understood that each of the holding magnets C_2 to C_5 is 25 not of sufficient power, when energized, to so attract the corresponding armature and its associated switching element, but that, when the corresponding armature has been attracted by the corresponding magnet, the holding coil is strong enough to hold it in attracted position after deenergization of the magnet.

The operation is as follows:

Some or all of the vehicle controlled contacts c_1 to c_5 may be brought into electrical communication with the conductor 1, by cars or trains arriving thereat, in any order in close succession, or simultaneously, for equal or unequal periods of time, which are co-incident in whole or only in part, with resultant energization of the corresponding some or all of magnets M_1 to M_5 which accordingly attract their armatures, which, however, are released only consecutively and in 40 a predetermined order of succession, with the result that the electromagnet S will receive a separate and distinct energization for each of the vehicle controlled contacts brought into electrical communication with the conductor 1, without any confusion in or overlapping of the control effects.

By way of example, let it be assumed that contacts c_1 , c_3 , c_4 and c_5 are so brought into electrical communication with the conductor 60 1. The result is the energization of the corresponding magnets M_1 , M_3 , M_4 and M_5 , which accordingly attract their armatures a_1 , a_3 , a_4 and a_5 into engagement with the contacts m_1 , m_3 , m_4 and m_5 , the corresponding 65 switch levers b_1 , b_3 , b_4 and b_5 riding up the in-

sulation on the backs of their corresponding contacts d_1 , d_3 , d_4 and d_5 and snapping over into position ready for return or downward movement. Upon engagement of armature a_1 with contact m_1 , current flows from the conductor 1 through the conductors 10 and 24, armature a_1 , contact m_1 and through all holding coils C_2 to C_5 to earth or return conductor E, these coils being therefore energized and holding the armatures a_3 , a_4 and a_5 in attracted positions after deenergization of magnets M_3 , M_4 and M_5 by passage of the vehicles beyond the corresponding vehicle controlled contacts. Since magnet M_2 is not energized, c_2 not having been brought 70 into engagement with conductor 1, the energization of coil C_2 has no effect, and the armature a_2 remains in the position illustrated in Fig. 1. Immediately the magnet M_1 is deenergized, by passage of the vehicle 75 beyond the contact c_1 , the armature a_1 and switch lever b_1 fall to normal position indicated in Fig. 1, and in so doing break connection a_1 and m_1 and close circuit through b_1 and d_1 , whereby current flows from conductor 1, through conductors 10 and 24, switch lever b_1 , contact d_1 , conductor 25, and through the winding S to earth or return conductor E, energizing the magnet S, which thereupon steps the wheel 6 around one step, 80 as and with the effects hereinbefore described. It being remembered that the contact between a_1 and m_1 persists until the armature a_1 has almost reached its normal position illustrated, and preferably until after 85 b_1 separates from d_1 , it will be seen that coils C_2 and C_3 will not be deenergized until armature a_1 has almost reached its normal position. Deenergization of holding coil C_2 has 90 no effect, since armature a_2 had not been attracted. But deenergization of holding coil C_3 allows the armature a_3 and its associated switch lever b_3 to fall to normal position, and in so doing the circuit of magnet S is 95 again closed for a period of time, with the result that the wheel 6 is again stepped around another notch or step. Contact between a_3 and m_3 persisting until the armature a_3 has almost reached its normal position, and preferably until after b_3 separates 100 from d_3 , holding coil C_4 is not deenergized until such time as switch lever b_3 has traversed its cooperating stationary contact d_3 . Then upon deenergization of holding coil C_4 armature a_4 falls, and wheel 6 is again 110 stepped around another notch or step by energization of the magnet S through contacts b_4 and d_4 ; and then finally holding coil C_5 is deenergized, whereupon the wheel 6 is 115 again stepped around another notch or step by energization of the magnet S through contacts b_5 and d_5 . It is accordingly true, then, that the magnet S has been consecutively and separately and distinctly energized by the falling of the armatures a_1 , a_3 , 120 a_4 and a_5 .

130

a_4 and a_5 in the order named, notwithstanding the fact that their corresponding vehicle controlled contacts c_1 , c_3 , c_4 and c_5 were brought into electrical communication with the conductor 1 within very short intervals of time, or simultaneously, and in a different order.

The resistances r_2 to r_4 serve the purpose of preventing corresponding holding coils C_2 to C_4 from being deenergized by shunting them through low resistance paths through the contacts m_2 , m_3 , etc.

From the foregoing it will be understood that the number of magnets and associated vehicle controlled contacts may be either greater or less than the number illustrated and described.

While in Fig. 1 I have described vehicle controlled contacts of the character of c_1 to c_5 all controlling magnet S for actuating a step-by-step mechanism or for setting signals, it will be understood that some of the magnets or solenoids may control a signal setting magnet while the others may control a signal clearing magnet. In other words, some of the magnets may control one magnet for any purpose and others may control one or more other magnets for any other purpose or purposes.

Such an arrangement is illustrated in Fig. 2 where the magnets M_1 and M_3 control the magnet S, while the magnets M_2 , M_4 and M_5 control the magnet K, which may be a signal clearing magnet for actuating the notched wheel 6 of the step-by-step mechanism in direction opposite to that effected by the magnet S. In this case the magnets M_1 and M_2 are controlled by the directionally responsive vehicle controlled switch comprising the contact c' which connects the contact c_1 with the conductor 1 upon vehicle movement toward the left, and connects contacts c_2 with the conductor 1 in response to vehicle movement toward the right. Similarly the vehicle controlled contact c'' connects contact c_3 with the conductor 1 in response to vehicle movement toward the left and connects contact c_4 with conductor 1 in response to vehicle movement toward the right. The mode of operation is otherwise that described in Fig. 1 as to successive release of the armatures of the magnets M_2 and M_5 . Some of these armatures, however, control only the magnets S, while others control magnet K, as described.

This same principle is obviously applicable to the arrangements of Figs. 4 and 5, in which a magnet or magnets in addition to S may be controlled by some of the magnets M_1 , etc.

In Fig. 3, one of the electro-magnets or solenoids, as M_1 , is shown as provided with a time element device for insuring that the core or armature of the controlled magnet, S, shall have time to complete its for-

ward and return strokes. It is to be understood that all of the magnets, M_1 to M_5 , of Figs. 1, 2, 4 and 5 may be so equipped.

The armature or core a' has secured thereto a rod 29 to which is pivoted at 30 a latch or hook 31 pressed by spring 32 against stop 33. A spring 34 raises the armature a' to its normal unattracted position, the bar 35 secured to said armature coming against a stop 36. To a stationary bracket 37 there is pivoted at 38 the long period pendulum 39 comprising the weights 40 and 41 disposed at the ends of arms of different lengths. Normally the pendulum rests in the position indicated against a stop 42. A lug 43 is secured to the pendulum and is adapted to be engaged by the latch or hook 31. The arm 44 carries a contact b' , connected with conductor 1, which is adapted to engage the contact d' carried on the end of the blade spring 45 normally engaging the stop 46, the contact d' being connected to one terminal of the magnet S, whose other terminal is connected to the earth or return conductor E.

The operation is as follows:

When the contact c_1 is brought into connection with conductor 1 by a passing vehicle, the magnet or solenoid M_1 is energized and the armature a' is attracted downwardly in opposition to spring 34. Immediately the armature a' starts downwardly the contact 47 carried thereby engages and connects the spring contacts 48 and 49, which is a modified form of contact m_1 of Fig. 1, to control the holding coil circuit. It will be understood, however, that more contacts may be made by supplying further spring contacts and bridging members, as for the purpose illustrated in Fig. 4, to take the place of contacts o_1 , p_1 , q_1 , etc.

By the downward stroke of the armature a' end of latch 31 engages lug 43 and is deflected in counter-clockwise direction about its pivot 30 in opposition to spring 32, which restores it to normal position after passing beneath the lug 43, the hook then engaging on the under side of the lug 43. When the magnet or solenoid M_1 is deenergized, the spring 34 returns the armature to normal position indicated and the latch 31 accordingly rotates the pendulum in counter-clockwise direction on its pivot 38, bringing contact b' into engagement with contact d' and in so doing deflecting the spring 45. The magnet S is accordingly energized. Due to the rotation of the pendulum, the hook 31 will disengage from lug 43, and the pendulum will then slowly return to normal position, the magnet S remaining energized until in the return movement the spring 45 engages stop 46, whereupon contact b' will separate from contact

a' and deenergize magnet S, whose armature or core will then make its return stroke as under influence of spring 3, as described in connection with Fig. 1.

5 By such an arrangement the armature or core of magnet S is insured ample time to complete a forward and return stroke, and the next magnet M_2 , or the like, of a series as in Figs. 1, 2, 4 and 5 is not allowed to 10 release its armature until contact 47 separates from contacts 48 and 49, for example, and this does not occur until armature a' has almost reached its normal position.

In the system illustrated in Fig. 4, holding 15 coils are dispensed with, and the magnets themselves employed to retain their armatures which are released in a predetermined order of succession.

In this system the armature a_1 is adapted 20 to engage three contacts o_1 , p_1 and q_1 , of which q_1 is connected through resistance s_2 with one terminal of the magnet M_2 , which is connected to the vehicle controlled contact c_2 . Contact p_1 is connected with contact p_2 and through resistance s_3 with the vehicle controlled contact c_3 and one terminal of magnet M_3 . Contact o_1 is connected with contacts o_2 and o_3 and through the resistance s_4 with one terminal of the magnet 25 M_4 and the contact c_4 . The armatures a_1 to a_4 are all connected to the conductor 1 through conductor 24 with which are connected also the contacts d_1 to d_4 , whose co-operating switch levers b_1 to b_4 are connected 30 to one terminal of the electro-magnet S, these switch levers being insulated from but actuated by their respective armatures.

The operation of the system as illustrated in Fig. 4 is as follows:

40 Whatever the number of magnets, or the order in which they are energized, their armatures will be released in a predetermined order of succession and cause distinct and successive energizations of the magnet S.

Assuming, for illustration, that magnets M_1 , M_3 and M_4 are simultaneously or substantially simultaneously energized, through their respective vehicle controlled contacts, 45 they will attract their armatures, armature a_1 into engagement with the three contacts o_1 , p_1 and q_1 , and a_3 into engagement with contact o_3 , and a_4 merely into engagement with its front stop. Armature a_2 , it will be 50 understood, has not been attracted. Accordingly, current will flow from conductor 1 through conductor 24 through armature a_1 and through contact q_1 and resistance s_2 through winding of magnet M_2 to earth or 55 return conductor E. The magnitude of the resistance s_2 is such that it limits the current through the magnet M_2 to such extent that attractive force produced by magnet M_2 is not sufficient to attract its armature a_2 , 60 but, having been previously attracted by

current delivered through contact c_2 , the attractive force would be strong enough to hold the armature a_2 attracted. However, in the present instance, the armature a_2 is not attracted, and therefore the effect of the 70 current passing through contact q_1 and resistance s_2 is *nil*. However, current also passes from armature a_1 through contact p_1 through resistance s_3 and thence through the winding of magnet M_3 to earth or return 75 conductor E, and since the armature a_3 has previously been attracted by current delivered to the magnet through the contact c_3 , this current is sufficient to hold the armature a_3 attracted, so long as armature a_1 is in engagement with contact p_1 . And simultaneously, current passes from armature a_1 to contact o_1 through resistance s_4 through 80 magnet M_4 , which has been previously energized through its contact c_4 , and therefore 85 retains the armature a_4 attracted so long as armature a_1 is in engagement with contact o_1 .

When magnet M_1 is deenergized, however, the armature a_1 falls and in so doing causes 90 closure of switch b_1 , d_1 to cause first energization of magnet S. Armature a_1 does not separate from its co-operating contacts until it has almost reached the limit of its downward travel, whereupon circuit is broken at 95 all of these contacts with the result that the current through magnet M_3 is interrupted, and its armature a_3 falls and causes the switch b_3 , d_3 to produce a second energization of magnet S. Though armature a_1 has 100 separated from its contact o_1 , the current through magnet M_4 is not interrupted because of the engagement of armature a_3 with contact o_3 , which allows current to pass from conductor 1, conductor 24, armature a_3 , contact o_3 , and resistance s_4 to the winding of 105 the magnet M_4 . In other words, after deenergization of magnet M_4 magnet M_3 holds the circuit of magnet M_4 closed. However, as armature a_3 falls, it eventually separates 110 from contact o_3 near the end of the downward travel of armature a_3 , thus finally interrupting the current through magnet M_4 which, upon deenergization, drops its armature a_4 with the result that the magnet S is 115 for a third time energized through switch b_4 , d_4 .

It will be understood that with each of the armatures a_1 to a_4 may be associated a time element device of the character described in 120 connection with Fig. 3.

In the system illustrated in Figs. 5 and 6, the restraint of the armatures after the magnets have been deenergized in response to departure of the trains or vehicles from their 125 associated vehicle controlled contacts, is effected by mechanical means.

The armatures a_1 to a_4 co-operate, respectively, with the cam levers t_1 to t_4 pivoted, respectively, to fixed supports, at u_1 to u_4 , 130

the cam levers t_1 to t_4 having the cam surfaces v_1 to v_4 , respectively, adapted to be engaged by the armatures a_1 to a_4 . The levers t_1 to t_4 have pin and slot or other suitable connections with their respective latch bars L_1 to L_4 , which are guided for longitudinal movement by any suitable guides, as rollers 28. The cam levers t_1 to t_4 are biased toward their normal positions by springs w_1 to w_4 , one end of each tension spring being connected to a cam lever, and its other end to a fixed part. The latch bar L_1 has pivoted thereto the latches x_2 to x_5 , coöperating respectively with the armatures a_2 to a_5 . 15 The latch bar L_2 has pivoted thereto the latches y_3 , y_4 and y_5 associated, respectively, with the armatures a_3 , a_4 and a_5 . The latch bar L_3 has pivoted thereto the latches z_4 and z_5 coöperating with the armatures a_4 and a_5 , 20 respectively. And the latch bar L_4 has pivoted thereto the latch z_6 coöperating with armature a_6 . Each of these latches is pressed by a spring 26 against a stop 27 on the corresponding latch bar. Each of the cam surfaces v_1 to v_4 is of such shape that when the corresponding armature is attracted, it will tilt the cam lever about its pivot in opposition to the spring and move the latch bar longitudinally and thereby carry the attached latches into the path of travel of the other armatures. And the latches are so shaped that if they are in position to which they have been actuated by the armature, the associated armature, if attracted, will deflect the latch against its spring 26 and ride up beyond its tip and rest upon the top of it, thus being restrained from falling or return stroke movement.

The operation of the system illustrated in Fig. 5 is as follows:

Assuming the magnet M_1 to be energized through its vehicle controlled contact c_1 , it will attract its armature a_1 upwardly, and in so doing deflect the cam lever t_1 with resultant movement of the latch bar L_1 which will carry the latches x_2 to x_5 with it. If, at the same time or shortly thereafter, another magnet, as M_3 , is energized through its vehicle controlled contact, its armature a_3 will be attracted upwardly and in so doing will engage and deflect the latch x_3 against its spring 26 and ride up above the latch, which will immediately be returned against its stop by the spring, and the armature a_3 will then be retained in attracted position after deenergization of magnet M_3 . And the upward movement of the armature a_3 has similarly actuated the cam lever t_3 to actuate the latch bar L_3 and the latches z_4 and z_5 carried thereby, so that if either or both of magnets M_4 or M_5 is simultaneously or substantially simultaneously energized, either or both armatures a_4 or a_5 will engage and deflect and then be held in attracted position by the latches z_4 and z_5 , respectively.

Assuming, however, that only magnets M_1 and M_3 are energized, upon deenergization of magnet M_1 its armature a_1 will fall and the switch d_1 , b_1 will cause the first energization of magnet S . The shape of the cam surface v_1 is such that, during the first part of the falling movement of the armature a_1 , the cam lever t_1 is kept in its deflected position, with the result that the latch bar L_1 and the attached latches are also kept in their deflected position. Near the end of the downward travel of the armature a_1 , that lower part of the cam surface v_1 is traversed which allows the spring w_1 to restore the latch bar L_1 , and latches carried thereby, to normal position. The result is that then the armature a_3 will drop, because the latch x_3 has been withdrawn from below it, and in falling the armature a_3 causes the switch d_3 , b_3 to give a second energization to the magnet S . And if the magnets M_4 and M_5 , for example, had also been energized, their armatures a_4 and a_5 would be successively released, with resultant successive independent energizations of magnet S .

And it will be understood that with each of the armatures a_1 to a_6 may be associated a time element device of the character described in connection with Fig. 3.

By all of the arrangements hereinbefore described, whatever may be the order of succession of the simultaneous or substantially simultaneous closure or rupture of a circuit at independent switch contacts, as vehicle controlled or other contacts, such circuit closures or ruptures will be caused to effect their ultimate controls in a predetermined order of succession and without overlapping or confusion.

And so far as the signaling art is concerned, it will be noted that a signal setting magnet, a signal clearing magnet, a step-by-step mechanism, a car counting mechanism, or any other translating device, which should be controlled separately and distinctly in response to various car or train movements, is so controlled, notwithstanding the fact that a plurality of train or car controls may be simultaneously or substantially simultaneously instituted. The effects of such simultaneously or substantially simultaneously instituted train or car controls produce their record or effect decidedly separately and dis-simultaneously.

It will be understood that my invention is in no wise limited to the number of magnets or relays M_1 , M_2 , etc., or their associated energizing or control circuits, for my invention may be present when only two contacts or circuits are adapted to control the electromagnet or translating device S , and may also be present with a greater number of magnets or relays and associated control contacts or circuits than herein illustrated.

It will be understood that the wheel 6 or

other step-by-step mechanism may be actuated, without recourse to an electromagnet as S, by any well known mechanical coupling between each of the armatures a^1 , a^2 , 5 etc., of Figs. 1 to 4, and the oscillating element carrying the pawl which actuates the wheel 6, this being an obvious equivalent of the arrangement shown. Any known mechanical connection by which the shaft of the switch disk 8 may be actuated by the armatures a^1 , a^2 , etc., may be substituted for the equivalent electro-magnetic connection shown; or each armature may so directly 10 actuate a wheel 6, all such wheels being mechanically connected to the same shaft.

It will be understood that if the armatures of the magnets M_1 , M_2 , etc., are manually or otherwise actuated, as, of course, they may be, the magnets and their system of 20 control would serve merely to retain the armatures for proper periods of time and insure their consecutive release as described.

What I claim is:

1. The combination with a translating device, of a plurality of magnets and their armatures controlling the same, means for energizing said magnets simultaneously or substantially simultaneously, and means preventing release of said armatures except in 25 predetermined order of succession, each of said armatures controlling said translating device only during one direction of movement.

2. The combination with a translating device, of a plurality of magnets and their armatures controlling the same, means for energizing said magnets simultaneously or substantially simultaneously, and means preventing release of said armatures except in 30 predetermined order of succession, each of said armatures controlling said translating device only during its movement after release.

3. The combination with a translating device, of a plurality of magnets and their armatures controlling the same, means for energizing said magnets simultaneously or substantially simultaneously, and means preventing release of said armatures except in 45 predetermined order of succession comprising for each magnet a circuit controlled by another of said magnets for maintaining said each of said magnets energized until after deenergization of said other of said 50 magnets, each of said armatures being independent of mechanical control by the others.

4. The combination with a translating device, of a series of magnets and their armatures controlling the same, switches controlling 60 said magnets simultaneously or substantially simultaneously, and means preventing movement of said armatures except in predetermined order of succession comprising a second switch for controlling each of said 65 magnets, the armatures of said magnets con-

trolling said last named switches in succession.

5. The combination with a translating device, of a series of magnets and their armatures controlling the same, switches for energizing said magnets simultaneously or substantially simultaneously, means preventing release of said armatures except in predetermined order of succession comprising for each magnet of the series a circuit adapted to energize a magnet to hold its armature, and switches controlled by said armatures in succession controlling said circuits. 70 75

6. In a signaling system, the combination with a plurality of circuits, of a switch for each of said circuits, movable means operating a plurality of said switches, a translating device adapted to be controlled by said circuits, a plurality of switches controlling the circuit of said translating device, an electro-magnet in each of said vehicle controlled circuits controlling one of said switches, and means insuring release of the armatures of said magnets in predetermined order of succession notwithstanding simultaneous or substantially simultaneous energization of said magnets. 80 85 90

7. In a signaling system, the combination with a plurality of vehicle controlled circuits, three or more in number, of a translating device adapted to be controlled by said circuits, a plurality of relays, one for each of said circuits, tongues of said relays controlling said translating device, and means releasing the tongues of said relays in predetermined order of succession. 95 100

8. In a signaling system, the combination with a plurality of vehicle controlled circuits, three or more in number, of a relay in each of said circuits, tongues of said relay, a translating device controlled by said relays, said translating device controlled only during movement of the tongues of said relays in one direction, and means preventing return of said relay tongues except 105 110 in predetermined order of succession.

9. In a signaling system, the combination with a plurality of vehicle controlled circuits, of a relay in each of said circuits, a tongue for each relay, a translating device controlled by said relays, said translating device controlled only upon return of the tongues of said relays to their normal positions, and means insuring return of said relay tongues to their normal positions successively. 115 120

10. In a signaling system, the combination with a plurality of vehicle controlled circuits, of a translating device adapted to be controlled thereby, a relay in each of said circuits, the movable member of each relay controlling the circuit of said translating device and controlling a magnetizing circuit of another relay for restraining the movable member thereof after termination 125 130

of its control by a vehicle controlled circuit, whereby said movable members of said relays return to their normal positions in succession.

11. In a signaling system, the combination with a plurality of vehicle controlled circuits, of a translating device adapted to be controlled thereby, a relay in each of said circuits, the movable member of each relay controlling the circuit of said translating device and controlling a magnetizing circuit of another relay for restraining the movable member thereof after termination of its control by a vehicle controlled circuit, whereby the movable elements of said relays return to their normal position in predetermined order of succession.

12. In a signaling system, the combination with a plurality of vehicle controlled circuits, a relay in each of said circuits, a translating device controlled by said relays, resistances, the windings of said relays controlled by others of said relays through said resistances limiting the current to such value as to prevent actuation of their movable members but to restrain said movable members after having been actuated by current in said control circuits.

13. The combination with a translating device, of a plurality of magnets and their armatures adapted to independently control the same, means for energizing said magnets simultaneously or substantially simultaneously, and means preventing release of said armatures except in predetermined order of succession, each of said armatures being independent of mechanical control by the others.

14. The combination with a translating device, of a plurality of magnets and their armatures controlling said translating device, means for energizing said magnets simultaneously or substantially simultaneously, means for restraining the armatures of said magnets after deenergization of said magnets, said armatures being released in succession in response to release of one or more of them.

15. The combination with a plurality of movable members each normally in one position, means for moving said members independently of each other to their other positions, means for holding said members in their said other positions after discontinuation of the forces moving them thereto, said members being released in succession in response to release of one or more of them.

16. The combination with a translating device, of a series of magnets and their armatures controlling the same, switches for energizing said magnets simultaneously or substantially simultaneously, means preventing release of said armatures except in predetermined order of succession comprising for each magnet of the series a circuit adapt-

ed to energize the magnet to hold its armature, and switches controlled by said armatures in succession controlling said circuits, said armatures controlling said translating device only during movement after their release.

17. The combination with a translating device, of a series of magnets and their armatures controlling the same, switches for energizing said magnets simultaneously or substantially simultaneously, means preventing release of said armatures except in predetermined order of succession comprising for each magnet of the series a circuit adapted to energize the magnet to hold its armature, and switches controlled by said armatures in succession controlling said circuits, said armatures controlling said translating device only during movement after their release, said armatures prolonging closure of the switches controlled thereby.

18. The combination with a translating device, of a series of magnets and their armatures controlling the same, switches for energizing said magnets simultaneously or substantially simultaneously, means preventing release of said armatures except in predetermined order of succession comprising for each magnet of the series a circuit adapted to energize the magnet to hold its armature, and switches controlled by said armatures in succession controlling said circuits, said armatures controlling said translating device only during movement after their release, said armatures prolonging closure of the switches controlled thereby, each armature prolonging during its release closure of the switch controlled thereby.

19. The combination with a translating device, of a series of magnets and their armatures controlling the same, means for controlling said magnets simultaneously or substantially simultaneously, and means preventing release of said armatures except in predetermined order of succession, said means insuring control of said translating device by said armatures in a predetermined order of succession and comprising a circuit for each of said magnets for prolonging the control thereof, and switches controlling said circuits and controlled by said armatures, the armature of one of said magnets controlling switches of the control prolonging circuits of the remainder of the magnets of the series, and the others of the armatures of said magnets controlling progressively less numbers of switches.

20. The combination with a translating device, of a series of magnets and their armatures controlling the same, means for controlling said magnets simultaneously or substantially simultaneously, and means preventing release of said armatures except in predetermined order of succession, said means insuring control of said translating

- device by said armatures in a predetermined order of succession and comprising a circuit for each of said magnets for prolonging the control thereof, and switches controlling said circuits and controlled by said armatures, the armature of one of said magnets controlling switches of the control prolonging circuits of the remainder of the magnets of the series, the others of the armatures of said magnets controlling progressively less numbers of switches accordingly as said armatures effect later controls of said translating device.
21. The combination with a translating device, of a series of magnets and their armatures controlling the same, means for energizing said magnets simultaneously or substantially simultaneously, and means preventing release of said armatures except in predetermined order of succession comprising for each of said magnets a circuit for maintaining the same energized independently of said first mentioned means, an armature when attracted closing and prolonging closure of said circuits of all magnets whose armatures are to be released later.
22. The combination with a translating device, of a series of magnets and their armatures controlling the same, means for energizing said magnets simultaneously or substantially simultaneously, and means preventing release of said armatures except in predetermined order of succession comprising for each of said magnets a circuit for maintaining the same energized independently of said first mentioned means, an armature when attracted closing and prolonging closure of said circuits of all magnets whose armatures are to be released later, each of said armatures controlling said translating device only during movement after its release.
23. The combination with a translating device, of three or more magnets and their armatures controlling said translating de-
- vice, release of any one of said armatures effecting operation of said translating device, means for energizing said magnets simultaneously or substantially simultaneously, and means preventing release of said armatures except in predetermined order of succession.
24. The combination with a translating device, of three or more magnets and their armatures controlling said translating device, a plurality of contact devices for controlling said magnets respectively, means for operating said contact devices simultaneously or substantially simultaneously, and means preventing release of said armatures except in predetermined order of succession.
25. The combination with a translating device, of a plurality of magnets and their armatures controlling said translating device, operation of said translating device being effected by the operation of any one of said armatures independently of the others, means for energizing said magnets simultaneously or substantially simultaneously, and means preventing release of said armatures except in predetermined order of succession.
26. The combination with a translating device, of a plurality of magnets and their armatures controlling said translating device, means for energizing said magnets simultaneously or substantially simultaneously, and means preventing release of said armatures except in predetermined order of succession, each of said armatures being independent of mechanical control by the others.

In testimony whereof I have hereunto affixed my signature in the presence of the two subscribing witnesses.

HORACE C. KNERR.
